INVENTOR.

Matthew Konzelman
BY

Geo. P. Kimmel, ATTORNEY.

UNITED STATES PATENT OFFICE.

MATTHEW KONZELMAN, OF PERU, ILLINOIS.

WRENCH.

Application filed March 30, 1927. Serial No. 179,534.

The invention relates to vise-tongs, and more particularly to the class of wrench vises of the tongs type.

The primary object of the invention is the provision of a tool of this character, wherein the gripping jaws for a piece of work, for example a pipe, are readily and easily adjusted to initially receive the work and thereafter the said jaws can be minutely adjusted to firmly grip and hold the work, these jaws being a part of handle levers, which can be aligned with each other, so that the same can be engaged in a socket or a clamp of a fixed part, whereby the tool will serve as a vise for firmly and securely holding the work to be operated upon.

Another object of the invention is the provision of a tool of this character, wherein the jaws and the lever handles are arranged in a novel manner, so that the tool may be utilized as a wrench in the ordinary manner or as a vise stationarily supported for firmly and securely clamping a piece of work to be operated upon, for example to effect the threading of pipes or other work.

A further object of the invention is the provision of a tool of this character, wherein the jaws are connected so that one jaw can be slidably adjusted relative to the other jaw and both jaws swung toward or away from each other for clamping action, the sliding jaw being capable of minute adjustment to assure firm and secure biting engagement of both jaws with the work to be operated upon for the secure holding thereof, when the tool is supported to serve as a vise and thus obviating the necessity of the removal of the tool from its support for the proper and accurate adjustment of the jaws relative to each other.

A still further object of the invention is the provision of a tool of this character, which is extremely simple in construction, strong, durable, thoroughly reliable and efficient, adaptable for use as a wrench, vise or tongs, quick adjustable, and inexpensive to manufacture.

With these and other objects in view, the invention consists in the features of construction, combination and arrangement of parts, as will be hereinafter more fully described in detail, illustrated in the accompanying drawing showing the preferred embodiment of the invention, and pointed out in the claims hereunto appended.

In the accompanying drawing:

Figure 1 is a fragmentary perspective view of a support, showing the tool constructed in accordance with the invention engaged therein for service as a vise for holding a piece of work.

Figure 2 is a fragmentary side elevation of the tool.

Figure 3 is a view similar to Figure 2 looking toward the opposite side of said tool.

Figure 4 is a sectional view on the line 4—4 of Figure 2.

Similar reference characters indicate corresponding parts throughout the several views in the drawing.

Referring to the drawing in detail, the tool comprises a pair of lever handles A and B, respectively, these being relatively long to assure proper leverage and are tapered toward their free ends. The lever handle A is straight throughout its extent, while the lever handle B has an outwardly bowed portion 5 for a purpose presently described.

Formed on the lever handle A at the wider or outer end thereof is an offset substantially yoke-shaped stationary jaw 6 and likewise formed on the wider end of the lever handle B is a movable jaw 7 relative to the jaw 6. The lever handle B has its outer or forward end formed with an inwardly disposed forwardly inclined extension 8 having its inner end merging into the inner end of an outwardly directed forwardly curved jaw 7 having its outer end inset to extend over jaw 6 to oppose or confront the forward arm or claw extension 9 of the jaw 6, when the handle levers A and B are connected together in a manner presently described.

The inner face of the claw extension 9 and the outer end of the jaw 7 are formed with serrated or toothed gripping surfaces 10. The gripping faces oppose each other so that when the jaws are engaged with a piece of work, for example a pipe C the latter will be securely and firmly gripped by the surfaces 10 of the jaws of the tool as will be apparent. The forward end of the movable jaw is rectangular and the rear face of the forward arm of the stationary jaw inclines rearwardly in opposite directions from the transverse median.

The jaw 6 is formed with a relatively long flat base or intermediate portion 11 provided with a longitudinally extending slot 12 for ac-

commodating a pivot bolt 13, the shank having a squared inner portion 14 slidably engaged in the slot 12 and a rounded outer portion 15 engaging a correspondingly shaped 5 hole 16 formed in the inner end of the jaw 7 for pivotally and slidably connecting said jaw 7 with the jaw 6. The bolt at one end carries a threaded nut 17 and is formed at its other end with a head 18.

10 Formed on the inner end of the jaw 6 at the outer face thereof is a laterally extending boss-like internally threaded eye 19 in which is engaged an adjusting screw 20, the inner end of which plays against the squared inner 15 portion 14 of the bolt 13 engaged in the slot 12, so that on the adjustment of the screw 20 the bolt 13 can be positively shifted in one direction in the slot 12. This screw 20 is utilized to obtain minute adjustment between 20 the jaws 6 and 7, which latter are capable of quick adjustment by their sliding and pivotal connection with each other. The outer end of the screw 20 has a wrench engaging head 21, so that the same can be readily adjusted when occasion 25 requires.

It will be readily apparent, in view of the foregoing description that the tool comprises two bars each having end portions offset in the same direction to mount a pivotal connection 30 between them, laterally spaced from the longitudinal line of the bars and with their ends set back into the longitudinal line of the bars so as to provide opposing jaw faces transversely across the line of the bars movable 35 upon the pivot to bring opposing thrusts in the line of the bars, as the latter are brought together to overlap each other, and with one of the lateral offset portions being longer than the other to provide the outer jaw and further slotted to permit of adjustment of 40 the pivot so that the jaws may be so placed that the thrust is exerted upon the work when the bars are overlapped throughout their length.

In one use of the tool the lever handles A 45 and B are shifted to align with each other and the same are forced into a socket 22 formed in a post or other support 23, so that the tool will be fixedly held thereby, although it is to be understood that such tool can be similarly engaged in a clamp or other character of support, the outwardly bowed portion 5 of the lever handle B being designed to act as a stop or abutment to limit the insertion of both lever handles A and B when in alignment with each 55 other in the said post, support or the like as

will be apparent. When the tool is mounted in the manner as shown in Figure 1 of the drawing it can be utilized as a vise, the jaws 6 and 7 being initially adjusted to freely receive work therebetween and thereafter such jaws minutely adjusted relative to each other by the screw 20 to firmly and securely clamp the work in the tool to be operated upon.

It is obvious that the tool can be utilized as an ordinary pipe wrench, tongs or for other uses as the occasion requires.

It will be apparent that by reason of the location of the screw 20 engaged in the eye 19 at the inner end of the stationary jaw 6, when the tool is engaged in the support 23, this screw 20 and the head 21 thereof will be readily and easily accessible, without any interference in the operation of the screw 20, either by the work held by the tool or the tool itself. This is also true when the tool is used as a wrench, because the screw 20 is exposed in a direction from the stationary jaw 6 to be freely engaged for minute adjustment of the movable jaw 7 as will be clearly apparent.

From the foregoing it is thought that the construction and manner of use of the tool will be clearly understood and therefore a more extended explanation has been omitted.

It is to be further understood that changes, variations and modifications may be made in the tool without departing from the spirit of the invention or sacrificing any of its advantages.

What is claimed is:—

A wrench comprising two bars, each having end portions offset in the same direction to mount a pivotal connection between them, said offset portions laterally spaced from the longitudinal line of the bars and with their ends set back into the longitudinal line of the bars to provide opposing jaw faces extending transversely across the line of the bars and movable on the pivot to bring opposing thrusts in the line of the bars, as the latter are brought together to overlap each other, one of said lateral offset portions being longer than the other to provide the outer jaw and slotted to permit adjustment of the pivot so that the jaws may be so placed that the thrust is exerted upon the work when the bars are overlapped throughout their length.

In testimony whereof, I affix my signature hereto.

MATTHEW KONZELMAN.
